UNITED STATES PATENT OFFICE.

FRANK C. GRIMM, OF CLEVELAND, OHIO.

SANITARY LOCKING BOTTLE-HOLDER.

1,107,667.

Specification of Letters Patent. Patented Aug. 18, 1914.

Application filed February 7, 1914. Serial No. 817,122.

To all whom it may concern:

Be it known that I, FRANK C. GRIMM, a citizen of the United States, and a resident of Cleveland, county of Cuyahoga, and State of Ohio, have invented a new and useful Improvement in Sanitary Locking Bottle-Holders, of which the following is a specification, the principle of the invention being herein explained and the best mode in which I have contemplated applying that principle, so as to distinguish it from other inventions.

The present invention relates to a holder adapted to receive bottles and the like and to prevent unauthorized removal of the same. A device of this sort is quite generally needed in cities, where the loss by theft of milk usually deposited on door-steps, porches and similar places has reached considerable proportions, and the present device is intended as a simple and effective check against any such unlawful removal of bottles or similar articles.

To the accomplishment of these and related ends said invention then consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

Figure 1 is a view in perspective of my device; Fig. 2 is a plan view of the same with the cover plate of the bracket removed; Fig. 3 is a section on the line 3—3 in Fig. 2; and Fig. 4 is a plan view indicating the method by which the device may be enlarged to take care of a greater number of bottles.

In Fig. 1 there is shown a hollow bracket 1 formed of a bottom portion 2 and a removable cover plate 3. This bracket is adapted to be attached by any suitable means to the side of a house or the side of steps or the like in a horizontal position. The bracket is provided with three spaced tongues 4, 5, and 6, thus providing between such tongues two recesses 7 and 8 which are formed preferably semi-circular and are adapted to receive the neck of the standard form of milk bottle. Pivotaly attached to the central tongue 5 is a retaining member 9 which is provided with two divergently extending arms 10 and 11, each of such arms being formed to coöperate with the nearest

adjacent recess in the bracket to hold therebetween a milk bottle as stated. It will be understood that the precise form of the recess is unimportant, it being only necessary that the recess and the adjacent arm be formed to coöperatively provide an opening adapted to receive the neck of a bottle and prevent the bottle from disengagement while the arm is in its coöperative position.

The arms are provided at their extremity with latch members 12 and 13 respectively adapted to be resiliently and automatically engaged by locking lugs 14 and 16 attached to resilient metal strips 14 and 17 suitably mounted in the tongues 4 and 6. These locking members 14 and 17 are rendered inoperative by means of two slidably mounted plates 18 and 19 which are inclosed in the bracket, the plate 18 normally extending into the recess 8 and the plate 19 similarly extending into the recess 7. These two plates are maintained in such normal position by means of springs 20 and 21 suitably mounted in the bracket. Movement of the plate 19 is normally prevented by means of a pivoted locking lug 22 which engages in a slot or recess 23 formed in the top of such plate, being maintained therein by means of a spring 24. This lock is rendered inoperative only when a key is inserted in the key-hole 25 formed in the upper surface of the bracket and turned, thus swinging the lug 22 out of the recess 23. A spring 26 is attached to the bracket and to the retaining member 9 and is adapted to normally position the latter, as shown in Fig. 2. Any suitable lock may be provided for this purpose as a combination lock may serve equally well although in general a lock of the present type will be sufficient. Any suitable number of tumblers may be used instead of but one (the lug 22) as here illustrated.

In operation, an empty bottle will be placed in the recess 7, the bottle being preferably inverted, where it will be held by the arm 10, the retaining member being in position shown in Fig. 1. When the milkman brings a full bottle he forces the same into the recess 8, thus displacing the plate 18 to the left and releasing the locking lug 13 from the latch 12. The spring 26 thereupon throws the retaining member into its other position, thus locking the full bottle into the recess 8. The full bottle can then be removed from the recess 8 by first inserting

the key in the key-hole and releasing the locking lug from its engagement in the plate 19, and then pressing against the projecting portion of such plate by means of an empty bottle or by the hand until this plate is displaced toward the right, thus causing the release of the locking lug 16 from the latch 15.

bottle or by the hand until this plate is displaced toward the right, thus causing the release of the locking lug 16 from the latch 15.

In Fig. 4 is illustrated a construction which may be used when more than one bottle is to be held at a time. The arms 30 in this type are double, each being adapted to coöperate with two recesses 31 in the bracket. It will be understood that more than two recesses may be provided on either side of the center of the bracket if desired although, in any case, but one set of locking means will probably be provided and these may obviously be most conveniently disposed in the two center recesses and on the coöperating portions of the two arms.

Former devices designed for similar purposes have been complicated in construction, involving the use of complete inclosures for the bottles, such as boxes, cabinets and the like, without giving as much actual security against theft as the present device. The latter is very simple and compact, provides a secure means for holding one or more bottles, and is convenient to operate.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In a locking retainer for bottles and the like, the combination of an open bracket, a retaining member shiftably attached to said bracket, said member being formed to coöperate with said bracket, in two different positions of said member, to retain a bottle therebetween in either of such two positions, and means adapted to lock said member in either position.

2. In a locking retainer for bottles and the like, the combination of an open bracket, a retaining member shiftably attached to said bracket, said member being formed to coöperate with said bracket, in two different positions of said member, to retain a bottle therebetween in either of such two positions; and means automatically operable upon movement of said member into either of such two positions, said means being adapted to lock said member against movement.

3. In a locking retainer for bottles and the like, the combination of an open bracket,

a retaining member shiftably attached to said bracket, said member being formed to coöperate with said bracket, in two different positions of said member, to retain a bottle therebetween in either of such two positions; and two independent locking members, each of said members being automatically operable, upon movement of said retaining member into one of such two positions, to lock said retaining member against movement. 75

4. In a locking retainer for bottles and the like, the combination of an open bracket, a retaining member shiftably attached to said bracket, said member being formed to coöperate with said bracket, in two different positions of said member, to retain a bottle therebetween in either of such two positions; and two independent resilient locking members, each of said members being automatically operable, upon movement of said retaining member into one of such two positions, to lock said retaining member against movement. 85

5. In a locking retainer for bottles and the like, the combination of an open bracket, a retaining member having two arms, said member being pivotally attached, intermediate its ends, to said bracket, each arm of said member being formed to coöperate with one part of said bracket, in two different positions of said member, to retain a bottle therebetween in either of such two positions, and means adapted to lock said member in either position. 95

6. In a locking retainer for bottles and the like, the combination of an open bracket, a retaining member having two arms, said member being pivotally attached, intermediate its ends, to said bracket, each arm of said member being formed to coöperate with one part of said bracket, in two different positions of said member, to retain a bottle therebetween in either of such two positions, and coöperative means mounted on said bracket and said member and adapted to lock said member in either position. 105

7. In a locking retainer for bottles and the like, the combination of an open bracket, a retaining member having two arms, said member being pivotally attached, intermediate its ends, to said bracket, each arm of said member being formed to coöperate with one part of said bracket, in two different positions of said member, to retain a bottle therebetween in either of such two positions, and two sets of coöperative locking means, each set being mounted on said bracket and said member and each set being adapted to lock said member in one of such two positions. 115

8. In a locking retainer for bottles and the like, the combination of a bracket, a retaining member having two arms, said member being pivotally attached intermediate its ends to said bracket, the latter being formed, 125

on either side of such point of attachment of said member, with a recess adapted to receive a bottle, said member having either arm formed to coöperate with said bracket to hold the bottle therebetween, and means adapted to lock said member in such position.

9. In a locking retainer for bottles and the like, the combination of a bracket having two adjacent recesses separated by a tongue, a retaining member including oppositely extending arms, said member being pivotally connected, at substantially its center, to such tongue on said bracket, each of such arms being formed to coöperate with the adjacent one of such recesses to hold a bottle therebetween, and locking means mounted on said bracket and adapted to lock said member against movement.

10. In a locking retainer for bottles and the like, the combination of a bracket having two adjacent recesses separated by a tongue, a retaining member including oppositely extending arms, said member being pivotally connected, at substantially its center, to such tongue on said bracket, each of such arms being formed to coöperate with the adjacent one of such recesses to hold a bottle therebetween, such arms being disposed at an angle to each other, whereby only one such arm is in position to coöperate with its adjacent recess at a time, and locking means mounted on said bracket and adapted to lock said member against movement, when one of such arms is in such coöperating position.

11. In a locking retainer for bottles and the like, the combination of a bracket having two adjacent recesses separated by a tongue, a retaining member including oppositely extending arms, said member being pivotally connected, at substantially its center, to such tongue on said bracket, each of such arms being formed to coöperate with the adjacent one of such recesses to hold a bottle therebetween, such arms being disposed at an angle to each other, whereby only one such arm is in position to coöperate with its adjacent recess at a time, means adapted to lock said member in one of such positions, and means operable by the positioning of a bottle in the unclosed one of such arms, and adapted to render said first-named means inoperative.

12. In a locking retainer for bottles and the like, the combination of a bracket having two adjacent recesses separated by a tongue, a retaining member including oppositely extending arms, said member being pivotally connected, at substantially its center, to such tongue on said bracket, each of such arms being formed to coöperate with the adjacent one of such recesses to hold a bottle therebetween, such arms being disposed at an angle to each other, whereby

only one such arm is in position to coöperate with its adjacent recess at a time, means adapted to lock said member in one of such positions; and a slidably mounted member adapted upon movement to render said means inoperative, said member normally projecting into the unclosed one of such recesses and being adapted to be operated by the positioning of a bottle therein.

13. In a locking retainer for bottles and the like, the combination of a bracket having two adjacent recesses separated by a tongue, a retaining member including oppositely extending arms, said member being pivotally connected, at substantially its center, to such tongue on said bracket, each of such arms being formed to coöperate with the adjacent one of such recesses to hold a bottle therebetween, such arms being disposed at an angle to each other, whereby only one such arm is in position to coöperate with its adjacent recess at a time; a resilient locking member mounted on said bracket and adapted to automatically engage one of such arms upon movement of the same into position to coöperate with its adjacent recess, and a plate slidably mounted on said bracket and adapted, upon movement, to render said locking member inoperative, said plate normally projecting into the unclosed one of such recesses and being adapted to be operated by the positioning of a bottle therein.

14. In a locking retainer for bottles and the like, the combination of a bracket having two adjacent recesses separated by a tongue, a retaining member including oppositely extending arms, said member being pivotally connected, at substantially its center, to such tongue on said bracket, each of such arms being formed to coöperate with the adjacent one of such recesses to hold a bottle therebetween, such arms being disposed at an angle to each other, whereby only one such arm is in position to coöperate with its adjacent recess at a time; a resilient locking member mounted on said bracket and adapted to automatically engage one of such arms upon movement of the same into position to coöperate with its adjacent recess, a plate slidably mounted on said bracket and adapted upon movement, to render said locking member inoperative, said plate normally projecting into the unclosed one of such recesses and being adapted to be operated by the positioning of a bottle therein, a resilient locking member mounted on said bracket and adapted to automatically engage one of such arms upon movement of the same into position to coöperate with its adjacent recess, and a plate slidably mounted on said bracket and adapted upon movement, to render said locking member inoperative, said plate normally projecting into the unclosed one of such recesses and being adapted to be operated by the positioning of a bottle therein.

15. In a locking retainer for bottles and the like, the combination of a bracket having two adjacent recesses separated by a tongue, a retaining member including oppositely extending arms, said member being pivotally

- connected, at substantially its center, to such tongue on said bracket, each of such arms being formed to coöperate with the adjacent one of such recesses to hold a bottle therebetween, such arms being disposed at an angle to each other, whereby only one such arm is in position to coöperate with its adjacent recess at a time; a resilient locking member mounted on said bracket and adapted to automatically engage one of such arms upon movement of the same into position to coöperate with its adjacent recess, a plate slidably mounted on said bracket and adapted, upon movement, to render said locking member inoperative, said plate normally projecting into the unclosed one of such recesses and being adapted to be operated by the positioning of a bottle therein, and a spring mounted on said bracket and engaging said retaining member, said spring being adapted, upon such movement of said plate, to move said retaining member into position to render such other arm effective.
16. In a locking retainer for bottles and the like, the combination of a bracket having two adjacent recesses separated by a tongue, a retaining member including oppositely extending arms, said member being pivotally connected, at substantially its center, to such tongue on said bracket, each of such arms being formed to coöperate with the adjacent one of such recesses to hold a bottle therebetween, such arms being disposed at an angle to each other, whereby only one such arm is in position to coöperate with its adjacent recess at a time; a resilient locking member mounted on said bracket and adapted to automatically engage one of such arms upon movement of the same into position to coöperate with its adjacent recess, a plate slidably mounted within said bracket and adapted, upon movement, to render said locking member inoperative, a spring also inclosed within said bracket and adapted to normally maintain said plate inoperative, said plate normally projecting into the unclosed one of such recesses and being adapted to be operated by the positioning of a bottle therein, a spring adapted, upon release of such last-named arm by said locking member, to move said retaining member into position to render such other arm operative, a second locking member inclosed in said bracket and adapted to engage such last-named arm, a second plate also slidably mounted within said bracket and adapted, upon movement, to render said second locking member inoperative, said second plate normally projecting into the now unclosed one of such recesses, and being operable upon the positioning therein of a bottle, and locking means adapted to normally prevent movement of said second plate.
- Signed by me, this 4th day of February, 1914.
- FRANK C. GRIMM.
